UNITED STATES PATENT OFFICE.

HORACE L. ARNOLD, OF NEW YORK, N. Y., ASSIGNOR TO JOHN A. HILL, OF SAME PLACE.

FLUID-ACTUATED MOTOR.

SPECIFICATION forming part of Letters Patent No. 666,840, dated January 29, 1901.

Application filed April 9, 1900. Serial No. 12,174. (No model.)

To all whom it may concern:

Be it known that I, HORACE L. ARNOLD, a citizen of the United States, residing in New York, (Brooklyn,) in the county of Kings and 5 State of New York, have invented certain new and useful Improvements in Fluid-Actuated Motors, of which the following is a specification.

My invention relates to motors driven by 10 any suitable fluid—for instance, steam or compressed air; and it has for one object the provision of a simple and compact machine of such construction that it will be in perfect standing and running balance and in which 15 the usual connecting-rods and crank-shaft are dispensed with.

A further object of the invention is the provision of a series of chambers, each constituting a cylinder, disposed around a common 20 axis and equipped with pistons the rods of which coöperate with a resistance-surface.

A further object of my invention is the provision of a carrier having a series of chambers, the end of the carrier constituting the 25 head for all of said chambers and each chamber having projecting therefrom a guide for the rod of the piston mounted within the chamber.

A further object of the invention is the provision, in connection with a series of cylinders, 30 of an inclined or cam-like resistance-surface against which the force of the pistons is directed and by which the reciprocatory movement of the piston is converted into rotary motion and the power-shaft of the motor is thereby actuated. Either the cylinder-carrier may be fixed to the motor-shaft and the cam or inclined surface be stationary or this construction may be reversed and the cam 35 be secured to the motor-shaft, while the cylinder-carrier having the series of chambers is stationary, for in each construction the result will be the same and reciprocatory motion will be converted into rotary motion.

A further object of the invention is the provision of antifriction-rollers or equivalent devices for coöperation with the pistons of the cylinders and the resistance or cam surface, whereby friction is reduced to a minimum.

A further object of the invention is the provision of cams through the instrumentality of

which the shaft is rotated and the pistons are returned to their starting positions in the chambers of the cylinder-carrier.

A further object of the invention is the provision of a valve of peculiar construction for regulating the admission of motive fluid to the piston chambers or cylinders, said valve being adjustable in such a way that it may be shifted either to drive the motor in a forward or a reverse direction, as circumstances require, or to vary the quantity of motive fluid supplied to the motor-cylinders or shut off the supply of said fluid.

In the accompanying drawings, Figure 1 is a longitudinal vertical section of a motor embodying my invention, taken on line xx , Fig. 2. Fig. 2 is a plan view, partially in section, of my improved motor. Fig. 3 is a side elevation of a form of valve employed detached from the motor. Fig. 4 is a right-hand end view of the valve. Fig. 5 is a transverse section of the valve on line aa , Fig. 3, looking in the direction of the arrow. Fig. 6 is a front end view of the motor. Fig. 7 is a rear end view of the motor. Fig. 8 is an end view of the motor-cylinder carrier with the head thereof removed, the valve and fluid-supply pipe being in section. Fig. 9 is a diagram of the main resistance surface or cam, graphically illustrating by dotted lines the position of a roller carried by one of the pistons as it traverses said surface. Fig. 10 is a similar view of the surface of the piston-controlling cam coöperating with the main cam. Fig. 11 is a side elevation of the cylinder, piston-guides, and shaft of the motor detached. Fig. 12 is a detail in section, illustrating the manner in which the rollers carried by the piston-rods of the motor are mounted. Fig. 13 is a perspective view of the ring for adjusting one of the cam-surfaces. Fig. 14 is a developed view of the valve, showing the ports in position for driving the motor in a forward direction. Fig. 15 is a similar view showing the ports of the valve in a different position relatively to the supply-ports of the motor. Fig. 16 is a developed view of the valve, showing the ports employed when it is desired to reverse the movement of the motor; and Fig. 17 is a similar view showing the valve-ports in a dif-

erent position with relation to the motor-supply ports.

Like numerals designate similar parts throughout the several views.

5 Referring to the drawings, the numeral 5 designates suitable framework composed, in the construction illustrated, of a base 5' and uprights 5², 5³, and 5⁴ for supporting the parts of the motor.

10 Journaled in bearings of the uprights 5³ and 5⁴ of the frame is a hollow shaft 6, carrying at one end a pulley or other power-transmitter 7, and integral with this shaft is a cylinder-carrier 9, having a series of piston-chambers or individual cylinders 10, 11, 12, and 13, projecting from each of which is a tubular longitudinally-slotted guide (designated, respectively, by the numerals 10', 11', 12', and 13') for accomplishing a purpose 15 thereafter set forth. Secured to the cylinder-carrier 9 is a disk 8, which constitutes the head for all of the cylinders 10, 11, 12, and 13, and projecting from said disk is a hollow journal 8', mounted in a bearing of the 20 upright 5³.

25 Mounted within the piston chambers or cylinders 10, 11, 12, and 13 are pistons 14, 15, 16, and 17, respectively, which are equipped at their ends with suitable antifriction devices, (shown as rollers 18 18'), although the invention is not limited to any particular device of this character. These rollers are mounted for free rotary movement on rods or bolts 19, secured in the end of each piston-rod, and one of said rollers rotates on an intermediate portion of the bolt 19 and is received within a slot 20 in the end of the piston-rod. Slots 21 are formed in each of the piston-rod guides for permitting free play of 30 the bolts, and said bolts subserve the further purpose of preventing rotation of the reciprocating pistons on their axes. Slots 20 are also formed in each piston-rod guide to receive the stationary resistance-cam 22. (See 35 Fig. 1.)

40 Coöperating with the rollers 18 is an inclined surface, (shown in the nature of a cam 22 and illustrated diagrammatically in Fig. 9,) and this cam-surface as the pistons are reciprocated to force the rollers 18 against the same causes the cylinder-carrier 9 to be moved in the line of least resistance, or, in other words, in a rotary path. Coöperating with this cam-surface 22 is a second cam-surface 23, having an undulatory outline, and against this last-named surface the roller 18' bears, and the two surfaces combine to cause the retraction of each piston and its rod at certain points in the rotation of the cylinder-carrier.

45 For the purpose of taking up wear or for adjusting for any reason the cam-surface 23, which is adjustably secured by bolts 80 passing through slots 81 in the wall of a shell or 50 casing 24, a threaded ring 25, (see Fig. 13,) having a series of spanner-holes 26, is threaded into said shell 24, and by turning this ring

the inner side thereof will bear against the piston-controlling cam-surface 23 and adjust the same. Shell 24 is, as shown in Fig. 1, 70 equipped with a base 24', through which suitable screws 27 are passed for securing the shell to the standard 5⁴ of the frame, and this base 24' is also cut out at a point concentric to its axis to receive the flanged portion 22' 75 of the cam-surface 22, bolts 28 serving to secure said cam-surface rigidly in position to said standard 5⁴. In this manner a very rigid and compact structure is provided, all danger of vibration or chattering of the framework and of the pistons coöperating therewith is avoided, and the shell acts to cover and protect the cam-surfaces and the piston-rod guides. Furthermore, the compact construction of the cylinder-carrier 9 and its attached parts serves in the manner of a fly-wheel to equalize the motion and store up power when the motor is in action.

80 Projecting from the carrier, and preferably integral therewith, is the main power-shaft 6 90 of the machine, which is cored out at 30 and has at the end opposite the journal 8' an extension 9², journaled in the bearings of the standard 5⁴, and to which extension a pulley 7 or other means for transmitting power is secured, as before stated.

95 Mounted within the journal 8' and shaft 6 is a valve of peculiar construction, which will now be described, and this valve consists, in the illustration given, of a cylindrical sleeve-like structure, (designated by 31,) on a reduced portion of which the hub 32 of the adjusting handle or lever 33 is secured, as shown in Fig. 1. This valve 31 is mounted for endwise reciprocation and adjustment 105 over a stationary fluid-supply pipe 34, said pipe being provided with a series of openings 35, through which the motive fluid escapes to the interior of the valve. Valve 31 is so mounted that it will be held stationary as regards rotative movement no matter how adjusted, and it is provided at a point intermediate its length with ports 36 and 37, through which when the valve is in the position shown in Fig. 1 motive fluid is allowed to pass and 110 enter, through ports 38 and 39, respectively, the chambers or piston-cylinders 14 and 16 to force the pistons thereof forward, and thereby cause the rods at the ends of said pistons, with their coacting rollers, to be driven 115 against the stationary inclined cam-surface 22 and rotate the shaft 6.

120 It will be observed that the ports or openings 36 and 37 of the valve 31 are of peculiar shape and that as the cylinder-carrier 9, with its ports 38 and 39 and 38' and 39', rotates over them from the position shown in the developed plan of the valve in Fig. 14 to that represented in Fig. 15, cut off of the motive fluid delivered by the pipe 34 will ensue and said 130 fluid will then be employed expansively to drive the pistons 14 and 16 forward, causing them to do their work.

135 Mounted in or secured in any suitable man-

ner to the handle 33 of valve 31 is a detent 40, (shown as a spring-actuated pin,) and this detent co-operates with any of a series of depressions or notches 41 in a holding-plate 42, 5 secured in any desirable manner to the standards 5² 5³ of the frame. By adjusting this valve endwise the ports thereof may be made to cover or uncover more or less of the openings 38 and 39 leading to the cylinders 10 12 10 of the carrier 9, and thereby the amount of motive fluid delivered to said cylinders may be regulated with nicety or the supply shut off at pleasure.

Referring to Fig. 3, it will be seen that the 15 body of the cylindrical valve is channeled out at 43 43' and the cylinders are so distributed around the axis of the valve that when one pair of cylinders—for instance, 10 and 12—is receiving motive fluid through 20 ports 36 and 37 of the valve the other pair of cylinders 11 13 is exhausting through ports 38' and 39' into the channels 43 43' of said valve. (See Fig. 8.)

Located at some distance from the ports 36 25 and 37 of the valve are other ports 44 and 45, which when the valve is adjusted to its limit within the shaft 30 will admit motive fluid to the pistons of the cylinders when the rollers of said pistons are on the portions of the 30 inclined surface or cam 22 which are utilized to give a reverse motion to the motor. In this manner by a simple adjustment of the valve the motor may be driven in one way or another way, as desired.

35 Any even number of single-acting cylinders and pistons may be used set in a circle about a common axis of revolution, the bore of the cylinders being parallel to said axis of revolution, and while I have shown in the drawings four cylinders and pistons it is distinctly to be understood that my invention is not limited to this number.

Each cylinder has a port adjacent to the cylinder-head on the side nearest the axis of 45 revolution, and the cylinders, the piston-rod guides projecting therefrom, and the shaft preferably constitute a single casting.

The middle portion of the cylinder-carrier 9' between the four cylinders is bored, in the 50 construction shown, to form a cylindrical seat for the valve 31, and, as above pointed out, this valve may be moved longitudinally to vary the point of cut-off and to stop, start, and reverse the motor, as desired. While 55 in the drawings this endwise motion of the valve is shown manually controlled, it is distinctly to be understood that the invention is not limited to such construction, for, as is obvious, the valve may be placed under the control of a governor, and it may also be constructed so as to cause the motor to turn in one direction only.

The exhaust from the cylinders passes through the center of the motor-shaft 6 and 60 leaves the motor at the driving-pulley end.

As shown, the pistons and piston-rods are integral, the latter projecting forward away

from the cylinder-heads and being preferably round in section and of such diameter that they will slide freely in the piston-rod guides 70 10' 11' 12' 13', which are axially coincident with the bores of the cylinders in which said pistons reciprocate. In the construction shown the cams 22 and 23 are so shaped and proportioned that they coact with the rollers 75 18 and 18' closely to control the pistons in their positions in the cylinders at all points in the revolution of the cylinder-carrier 9, and these rollers traverse the undulatory surfaces of both the cams. 80

In some constructions the piston-controlling cam 23 may be dispensed with; but it is, however, conducive to even wear and perfect control of the positions of the pistons to employ said cam, for the rollers being in rapid 85 action on the undulatory cam-surface are better kept in absolute contact with said surface by said cam than by weight, spring, or elastic pressure, for the latter can only be relied upon to preserve the contact between the 90 rollers and the main cam-face within certain speed limits, and if said rollers are not kept constantly in contact with the cam-face chattering and vibration occur, detrimental to the life of the machine. 95

When the valve 31 is in its mid-position, the ports in the cylinders communicate with the exhaust-spaces 43 43' only, and when said valve is moved a little either way the motive fluid is admitted between the cylinder-heads 100 and the pistons at the proper time to cause said pistons to advance.

As will be understood, the admission-ports of the valve 31 are enlarged laterally as they recede from the mid-position, so that the farther the valve is moved in either direction from its mid-position the greater will be the supply of motive fluid to the pistons in their cylinders, this continuing up to the limit set by the precise design of the valve-port openings shown; but the invention is not limited to any particular form of valve-port openings, for these may be modified as desired. In the drawings the ports are so constructed that the motive-fluid admission is from zero to 115 nearly one half the piston-stroke, expansion being relied upon to drive the piston through the final half of each working stroke, and the valve may be so set that it will govern the admission lead, which would in some degree 120 take work off the cam 23 and its rollers 18'; but as the cams are very easy in their angles the admission lead and exhaust compression are not so important as they would be with crank-connected piston-motors. 125

The cams may be variously constructed and may have either a single rise or a single fall in a complete circle, or two or more rises or falls. If the cams have only one rise and one fall in the cam-circle, then each piston 130 will make one double stroke—that is to say, one working stroke and one idle exhaust-stroke—for each full revolution of the motor-cylinders about the motor-shaft axis, and if

the cams have two rises and two falls of cam-surface then the piston will make two double strokes for each revolution of the cylinders and with a suitably-ported valve will make 5 two working strokes and two exhaust-strokes while the cylinder-carrier 9 makes a full revolution about the axis of the shaft 30. Preferably I employ cams, as shown in the drawings, having two rises and two falls and a 10 double-ported valve, so that each piston makes two working strokes for each revolution of the cylinders; but my invention is not limited to this construction. Four cylinders and four pistons are shown, and with this arrangement 15 two of the pistons are always acting on the stationary cam 22 to cause the motor-shaft to revolve. If the cams are symmetrical and the pistons are of the same individual weight, then, since the pistons reciprocate longitudinally 20 in pairs both back and forth, if the motor is in standing balance it will also of necessity be in running balance. In the construction shown the cam-surfaces (illustrated diagrammatically in Figs. 9 and 10) cause the 25 rollers carried by the pistons to conform in their movements substantially to the movement of a wrist-pin carried by a wheel or disk. (Shown in dotted lines in each of said views.) As before stated, however, these cam-surfaces 30 may be variously constructed without departure from my invention.

The invention is not limited to the precise details illustrated and described, nor is it essential that the parts be arranged and proportioned exactly as set forth. It has been found, however, in practice that the construction described is very simple and compact, runs in perfect balance and without vibration, and is peculiarly adapted for use in driving 35 automobiles or motor-vehicles or other machines or devices for which it is designed.

Having described my invention, I claim—

1. In combination, with a cylinder and its piston, an inclined resistance-surface coöperating with the piston-rod; a power-transmitting medium set in motion by said elements; a guide projecting from the cylinder and serving to prevent axial rotation of the piston; means carried by the piston-rod and traveling in said guide; a stationary piston-controlling cam located adjacent to and opposite the inclined resistance-surface; and antifriction devices carried by the piston-rod and located in the groove formed between the resistance-surface and said cam.

2. In combination with a cylinder and its piston, a resistance-cam; a roller carried by the piston-rod and in engagement with the resistance-cam; a guide projecting from the cylinder; a device carried by the piston-rod and working in said guide; a stationary piston-controlling cam; and a roller carried by the piston-rod and in engagement with said cam.

3. In combination with a cylinder and its piston, a resistance-cam; a roller journaled in a slot of the piston-rod and bearing against

said cam; a slotted guide projecting from the cylinder; a bolt on the piston-rod entering the slots of the guide, and carrying a roller 70 at its end and a piston-controlling cam with which said roller is in engagement.

4. The combination, with a carrier containing a series of concentrically-disposed cylinders each having a port and a slotted piston-rod guide, of means for supplying motive fluid to said cylinders; a series of pistons mounted in said cylinders; a shaft projecting from the carrier and having journals mounted in bearings of the frame; a casing; a resistance-cam mounted within said casing and projecting into the slots in the piston-rod guides; a piston-controlling cam; and rollers carried by the piston-rods and in engagement with the resistance and piston-controlling cams. 85

5. The combination, with a series of cylinders and their pistons, of a series of slotted guides projecting from said cylinders; devices carried by the piston-rods and traveling in the slots of said guides; a resistance-cam coöperating with the piston-rods; a shaft rotated by said piston-rods and resistance-cam; a stationary piston-controlling cam disposed adjacent to the resistance-cam; and antifriction devices carried by the piston-rod and bearing 95 against the resistance-cam and the piston-controlling cam.

6. The combination, with a series of cylinders and their pistons, of a disk-like head for said cylinders, said head having a journal; a hollow shaft journaled in the frame; an adjustable valve located within said shaft, said valve having ports for governing the supply of motive fluid to the cylinders; and a resistance-surface coöperating with the piston-rods 105 of said cylinders.

7. The combination, with a carrier having a series of cylinders, of a series of slotted guides projecting from the cylinders; a series of pistons mounted in said cylinders; rollers carried by bolts on the piston-rods, said bolts projecting into the slots of said guides; a cam-surface coöperating with said rollers; a piston-controlling cam; and rollers carried by the bolts and bearing against said piston-controlling cam. 115

8. The combination of a carrier, having a series of cylinders, each having a slotted piston-rod guide; of a hollow shaft integral with said carrier and journaled in the frame; a 120 valve mounted for longitudinal adjustment within said shaft; ports connecting said valve with the cylinders; a series of pistons mounted in the cylinders; devices carried by the piston-rods and movable in the slotted guides; 125 antifriction devices carried by the piston-rods and a resistance-cam and a piston-controlling cam with which said antifriction devices are in engagement.

9. The combination, with a carrier having 130 a series of cylinders, of a disk constituting the head for all of the cylinders; a hollow journal carried by the disk and mounted in a bearing of the frame; a tubular shaft pro-

- jecting from the carrier and also mounted in a bearing of the frame; a series of pistons mounted in the cylinders of the carrier; a stationary cam coöperating with the rods of 5 said pistons; a cam for controlling the movements of the pistons and coöperating with said stationary cam; and valve mechanism for controlling the supply of motive fluid to the cylinders.
10. The combination, with a cylinder and its piston, of a resistance-cam; a casing surrounding said cam; a piston-controlling cam adjustably mounted in said casing and anti-friction devices carried by the piston-rod and 15 in engagement with said cams.
11. The combination, with a cylinder and its piston, of a resistance-cam; a casing surrounding said cam; a piston-controlling cam; and means for adjusting one of said cams with 20 relation to the other cam.
12. The combination, with a carrier having a series of cylinders, of a series of pistons mounted within said cylinders and each having a projecting piston-rod; antifriction devices carried by said piston-rods; resistance and piston-controlling cams with which said antifriction devices are in engagement; a casing surrounding said cams; and means carried by the casing for adjusting one of said 25 cams with relation to the other cam.
13. The combination, with a cylinder and its piston, of a casing; a resistance - cam mounted within said casing; a piston-controlling cam also mounted within the casing; 30 a ring threaded into the casing for adjusting said piston-controlling cam; and antifriction devices carried by the piston and in contact with the resistance and piston - controlling cams.
14. The combination, with a carrier having a series of concentrically-disposed cylinders, each having a piston-rod guide, of a casing surrounding said piston-rod guides; a resistance-cam located within said casing; a piston-controlling cam located within the casing opposite to said resistance-cam; a series of pistons having rods, each rod carrying a device movable in the piston-rod guide; and anti-friction-rollers carried by said device and in 45 engagement with the resistance and piston-controlling cams.
15. The combination, with a carrier having a series of concentrically-disposed cylinders, of a plate closing the ends of all of said cylinders, said plate having a hollow journal; a tubular shaft connected with the carrier; a series of pistons mounted in the cylinders of the carrier; resistance and piston-controlling cams by which the piston-rods are controlled 50 in their movements; a casing surrounding said cams; means for admitting motive fluid to the cylinders; and a longitudinally-adjustable valve located within the hollow journal and tubular shaft for regulating the supply of such motive fluid to said cylinders.
16. A carrier provided with a series of cylinders concentric to its axis and having integral with said carrier a tubular shaft, in combination with a disk secured to one end of of the carrier and having a tubular journal; a series of pistons mounted in the cylinders of the carrier; a resistance-surface coöperating with the piston-rods to cause rotation of the carrier and shaft; and means for supplying motive fluid to the cylinders. 75
17. The combination, with a carrier having a series of cylinders, of a series of pistons mounted in said cylinders; a series of slotted piston-rod guides projecting from the carrier in line with the cylinders; a stationary resistance-cam projecting into the slots of said guides; a stationary piston-controlling cam; and antifriction devices between the piston-rods and said cams. 80
18. The combination, with a carrier having a series of cylinders, of a series of pistons mounted in said cylinders; a series of slotted piston-rod guides projecting from the carrier; a stationary resistance-cam entering the slots of said piston-rod guides; rollers carried by the piston-rods; and a stationary cam coöperating with said resistance-cam to control the movements of the pistons. 85
19. The combination, with a carrier having a series of cylinders, of a series of pistons mounted in said cylinders; a series of slotted piston-rod guides projecting from the carrier; a stationary resistance-cam entering the slots of said piston-rod guides; cross-bolts carried by the piston-rods; rollers journaled on said 90 bolts and entering the slots in the piston-rods; rollers journaled on the free ends of said bolts; and a piston-controlling cam with which said last-named rollers coöperate. 95
20. The combination, with a series of cylinders, of means for regulating the supply of motive fluid to said cylinders; a series of pistons mounted in said cylinders; an undulatory resistance-surface; antifriction devices carried by the piston - rods and operating 100 against said surface; a stationary piston-controlling cam; antifriction devices carried by the piston-rods and coöperating with said cam; and means for adjusting said cam. 105
21. The combination, with a rotative carrier having a series of cylinders, and with a tubular shaft integral with said carrier, of a disk for closing one end of said carrier, said disk having a tubular journal; a series of pistons mounted in the cylinders of the carrier; a resistance-surface coöperating with said pistons; a fluid-supply conduit mounted within the hollow journal and tubular shaft; and an adjustable valve for controlling the passage of fluid from said supply-pipe to the 110 ports of the cylinders. 115
22. The combination, with a cylinder and its piston, of a tubular shaft; a fluid-supply pipe located within said shaft; and an end-wise-adjustable valve surrounding said supply-pipe and having a port communicating with the port in the cylinder. 120
23. The combination, with a carrier having a series of cylinders, of a tubular shaft; a se- 125 130

ries of pistons mounted in said cylinders; a fluid-supply pipe located within the tubular shaft; a valve sleeved on said fluid-supply pipe and having ports for controlling the passage of motive fluid from said supply-pipe to the cylinders; and means for adjusting said valve.

24. The combination, with a rotative carrier having a series of cylinders, of a disk 10 constituting a head for all of said cylinders and carrying a journal; a hollow shaft projecting from the carrier; a series of pistons mounted within the cylinders; a resistance-cam coöperating with the pistons; a fluid- 15 supply pipe mounted within the tubular shaft; a valve sleeved on said pipe and having a series of ports; and means for effecting an endwise adjustment of said valve.

25. The combination, with a carrier having 20 a series of cylinders, of a tubular shaft; a hollow journal projecting from said carrier; a fluid-supply pipe mounted within said journal and shaft; a valve sleeved on said supply- 25 pipe and equipped with a series of ports for regulating the passage of motive fluid to the cylinders; a series of pistons mounted within the cylinders; a resistance-surface coöperating with the pistons; a piston-controlling cam; and means for adjusting the valve to control 30 the admission of motive fluid to said cylinders.

26. The combination, with a carrier having a series of cylinders each having a port, of a series of pistons and piston-rods mounted in 35 said cylinders; a fluid-supply pipe; a valve sleeved on said fluid-supply pipe and having a series of ports for controlling the passage of fluid from said supply-pipe to said cylinders; means for longitudinally adjusting said 40 valve; and a resistance-surface coöperating with the pistons of said cylinders.

27. The combination, with a carrier having a series of cylinders each equipped with a port, of a series of pistons and their rods 45 mounted in said cylinders; a resistance-cam; a shaft connected with the carrier; a fluid-supply pipe; a valve sleeved on the supply- 50 pipe and having ports of gradually-increasing area; and means for longitudinally adjusting said valve.

28. The combination, with a carrier having a series of cylinders, of pistons and their rods carried by said cylinders; a series of piston-rod guides projecting from the cylinders; a 55 tubular shaft projecting from the carrier; resistance and piston-controlling cam-surfaces; antifriction devices carried by the piston-rods and coöperating with said cam-surfaces; a fluid-supply pipe mounted within the tubular 60 shaft; and a valve having a series of ports mounted for endwise adjustment on said fluid-supply pipe.

29. The combination, with a carrier having a series of cylinders and a tubular shaft, of 65 pistons and their rods inserted in said cylinders; a plate constituting the head for all the cylinders and having a hollow journal; a per-

forated fluid-supply pipe mounted within said journal and shaft; a valve sleeved on the fluid-supply pipe and having a series of ports; means for adjusting said valve; a resistance-cam against which the force of the pistons is directed; a piston-controlling cam; and anti-friction devices carried by the piston-rods and located between said cams.

30. The combination, with a carrier having a series of cylinders, of a series of pistons and their rods mounted in said cylinders; a resistance-cam; a shell or casing surrounding said cam; a piston-controlling cam; antifriction devices between said cams; and a ring threaded into the casing for adjusting one of said cams with reference to the other.

31. The combination, with a carrier having a series of cylinders, each cylinder being provided with a slotted piston-rod guide, of a series of pistons and their rods mounted within said cylinders and said guides; a bolt carrying rollers located at the end of each piston; a resistance-cam with which one set of said rollers coöperates; a piston-controlling cam with which the other set of rollers coöperates; and means for adjusting said piston-controlling cam.

32. The combination, with a carrier having a series of cylinders each equipped with a port, of a series of pistons and their rods mounted in said cylinders; a series of slotted piston-rod guides projecting from the cylinders; a resistance-cam; rollers movable in slots of 100 the piston-rods and coöperating with said cam; a piston-controlling cam; rollers carried by the piston-rods and coöperating with said piston-controlling cam; a shell or casing surrounding said cams; and a ring threaded 105 into said casing for adjusting the piston-controlling cam.

33. The combination, with a carrier having a series of cylinders, of guides projecting from said cylinders; a series of pistons and their rods mounted within said cylinders and guides; a shaft connected with the carrier; a resistance-cam against which the force of the pistons is directed; a cam for controlling the movements of the pistons; and a valve 115 having ports for admitting motive fluid to said cylinders and having passages for receiving the exhaust from the cylinders.

34. The combination, with a series of cylinders, of pistons mounted in said cylinders; a fluid-supply pipe; and a valve sleeved on said pipe and having ports for admitting motive fluid to the cylinders, and exterior channels intermediate the ports for receiving the exhaust from the cylinders.

35. The combination, with a series of cylinders and their pistons, of a resistance-surface coacting with the piston-rods; a shaft rotated by the coöperation of said elements; and a valve having ports for admitting motive fluid simultaneously to a pair of cylinders and also having exterior channels for receiving the exhaust from said cylinders.

36. The combination, with a series of cyl-

inders and their pistons, of a resistance-surface against which the force of the pistons is directed; a shaft rotated by said elements; a valve having direct - action and reversing 5 ports and exterior channels for receiving the exhaust; and means for longitudinally adjusting said valve.

37. The combination, with a series of cylinders and their pistons, of a tubular shaft 10 connected with said cylinders; a fluid-supply pipe mounted within said tubular shaft; a valve having a series of ports for supplying motive fluid to the cylinders in pairs, and

also having a series of reversing-ports; means for adjusting said valve endwise within the 15 tubular shaft; a resistance-surface coöperating with the piston-rods; a shell or casing surrounding said resistance-surface; a cam located within said shell or casing; and a threaded ring having a series of spanner- 20 holes for adjusting said cam.
